UNITED STATES PATENT OFFICE.

THOMAS JEFFERSON KIRKPATRICK, OF SPRINGFIELD, OHIO.

BICYCLE-SADDLE.

SPECIFICATION forming part of Letters Patent No. 289,272, dated November 27, 1883.

Application filed July 11, 1883. (No model.)

To all whom it may concern:

Be it known that I, T. J. KIRKPATRICK, of Springfield, in the county of Clarke and State of Ohio, have invented certain Improvements 5 in Bicycle-Saddles, of which the following is a specification.

This invention relates more particularly to improvements upon the bicycle-saddle for which Letters Patent of the United States were 10 granted to me on the 29th day of May, 1883, No. 278,560.

The improvement consists, mainly, in combining with the frame or tree having elevated ends and a flexible seat suspended therefrom 15 winding-drums and locking devices located at the front, as a means of straining the flexible seat and giving the same the required tension.

Referring to the accompanying drawings, Figure 1 represents a perspective view of my 20 improved saddle. Fig. 2 is a longitudinal section of the same on the line *xx*. Fig. 3 is a top plan view of the frame or tree, having the seat or saddle proper removed therefrom.

A represents the tree or frame, the rear end 25 of which is elevated and curved to sustain and give form to the rear end of the saddle, while its forward end is forked to pass on opposite sides of the head of the machine, and adapted to sustain the forward ends or arms of the seat, 30 which are forked to correspond, as in my original patent, above referred to. The forward arms, *a*, of the frame are each provided with an elevated bar, *b*, and below and in rear of said bar with a transverse roller, *c*, the outer 35 end of which is made of angular form, as shown at *d*, to seat a wrench or other rotating device, and provided with a ratchet-wheel, *e*, which is engaged and prevented from turning backward by a pawl, *f*, pivoted to the frame.

40 B represents the seat or saddle proper, consisting of a sheet of flexible or pliable material secured at its rear end rigidly to the upper rear edge of the tree, and having its two forward arms or ends passed over the respective bars *b* and secured to the rollers or drums *c*, so that upon rotating said drums they are 45 caused to apply a longitudinal strain or tension to the saddle, which is suspended at its ends only. By tightening the drums I am enabled to apply any required degree of tension to

the saddle, and thus to render the same more or less elastic and to adapt it to riders of different weights. The fact that the two drums are adjustable independently of each other admits of the strain being applied to the two sides of 55 the saddle independently, thus securing equal stiffness at the two sides, notwithstanding the variable elasticity of the material at different points. While it is preferred to make use of the rollers or drums as the most simple and 60 convenient means of straining the saddle, screws or equivalent devices may be substituted therefor.

In order to prevent the chafing of the rider's 65 limbs upon the edges of the saddle, I provide the seat or saddle proper on each side of its neck or contracted portion with a downwardly-curved extension, *g*. These extensions or flaps are preferably formed in one piece with the saddle proper, and being curved downward, as shown, they afford an elastic rounded edge and adapt the saddle to sustain the 70 weight of the rider in an easy and comfortable manner.

The frame may be constructed of sheet-steel, 75 malleable iron, or other suitable material, it being preferred in practice to stamp the entire frame in one piece from sheet-steel, this method of construction securing strength, lightness, and elasticity. While the elasticity of the saddle or seat proper is relied upon mainly to render the saddle yielding, it is found in practice that when the frame or tree is made sufficiently light it will yield to a limited extent under strain, and serve the additional purpose 80 of a spring. It is to be observed that when in action the seat or saddle rises and falls in a vertical direction and without longitudinal motion, this characteristic being an important one, in that it avoids the danger of the rider 85 being thrown over the head of the machine. While the seat divided at the forward end is preferred, the device may be used at the front of a suspension-seat which is not divided.

The present invention is restricted to those 90 matters and things which are hereinafter claimed, and as to all matters which may be described or shown, but which are not claimed, the right is reserved to make the same the subject of a separate application.

I am aware that saddles have been hitherto constructed in which an elastic sheet constituting the seat proper was combined with a frame having upturned ends, from which the seat was suspended by rigid connections.

I am also aware that sectional saddle frames or trees have been provided with adjusting devices in various forms, for the purpose of permitting variations in the tension of the seat; but, so far as I am aware, such devices have universally failed to give satisfaction, and have therefore been practically abandoned.

Having thus described my invention, what I claim is—

15 1. In combination with the saddle tree or frame having its ends raised and its forward end

forked or bifurcated, and two independent positively-acting adjusting devices, substantially as described, acting upon the forward ends of the seat, whereby the two sides may 20 be adjusted positively and independently.

2. The saddle frame or tree having the forked forward end, the independent rollers, and their locking devices located in such forward ends of the fork, and the flexible seat having at the 25 front the two arms connected to the respective rolls.

THOMAS JEFFERSON KIRKPATRICK.
